UNITED STATES PATENT OFFICE.

GEORGE F. CASTLE, OF EAST CLEVELAND, OHIO, ASSIGNOR OF ONE-HALF TO LEWIS D. CASTLE, OF EAST CLEVELAND, OHIO.

ACCELERATOR FOR AUTOMOBILES.

Application filed June 2, 1922. Serial No. 565,387.

To all whom it may concern:

Be it known that I, GEORGE F. CASTLE, a citizen of the United States, and a resident of East Cleveland, county of Cuyahoga, and State of Ohio, have invented a new and useful Improvement in Accelerators for Automobiles, of which the following is a specification, the principle of the invention being herein explained and the best mode in which 10 I have contemplated applying that principle, so as to distinguish it from other inventions.

It is well known that most operators of self-propelled vehicles (automobiles, trucks, etc.) prefer to control the driving speed of such vehicle by means of the so-called foot accelerator instead of by means of the jointly operable hand-control lever. The use, however, of such foot actuated accelerator not only imposes a considerable physical strain on the driver, but also where a rough or bumpy road is being traversed, it is practically impossible to hold the accelerator steadily in any one position, with the 20 result that severe shocks are given to the engine and other working parts of the machine.

The object of the present invention, accordingly, is the provision of means where- 30 by the operator may be relieved of the necessity for constant attention to the control in question, allowing him to remove his foot to a more restful position, if he desires to do so. At the same time such operator may 35 instantly assume complete control of the speed of his engine through the accelerator whenever he desires to do so. I, furthermore, provide for a slight acceleration without rendering the speed control inoperative, 40 the present device being designed so that it can be set by the foot to maintain a normal speed, such speed slightly increased without changing the setting or at the will of the operator complete control of the speed re- 45 sumed through the foot pedal or accelerator. To the accomplishment of the foregoing and related ends, the invention, then, consists of the means hereinafter fully described and particularly pointed out in the claims, the 50 annexed drawings and the following description setting forth in detail certain

mechanism embodying the invention, such disclosed means constituting, however, but several of various mechanical forms in which the principle of the invention may be 55 used.

In said annexed drawings:—

Fig. 1 is a plan view of a preferred form of construction embodying my present improvements; Fig. 2 is a side elevation of 60 the same; Fig. 3 is a vertical section of a detail, the plane of the section being indicated by the line 3—3, Fig. 1; Fig. 4 is a plan view and partial section of a modified form of construction; Fig. 5 is a side eleva- 65 tion of such modified form; and Fig. 6 is a front elevation of still a third form of construction embodying the present improvements.

In the several forms of the device illus- 70 trated in the drawings, the accelerator pedal 1 is shown as of the vertically reciprocal type quite generally employed on various makes of automobiles, the stem of such pedal extending downwardly through the floor 2 75 of the vehicle and being connected with the engine throttle in the usual way. As ordinarily operated, the driver simply rests the heel of one foot on the floor adjacent such pedal and by rocking his foot presses the toe 80 or ball thereof on the pedal in order to produce such change in speed as may from time to time be desired. Obviously, however, it is not possible to rest the weight of the foot 85 on the pedal, but the foot must be maintained at the proper angle, imposing a constant strain on the driver, as aforesaid.

One principal element of the present de- 90 vice, in the form shown in Figs. 1, 2 and 3, is a foot rest 3 that is mounted adjacent such accelerator pedal 1 so as to be vertically reciprocal, in the same manner as is said pedal. Laterally projecting from the rest is an arm 4 that engages with the top of the pedal in order to press the latter down- 95 wardly when desired, the pedal being of relatively light construction so that its mere weight thus resting on the pedal does not materially affect the position of the latter. It will be understood that the relative loca- 100 tion of the pedal and rest may vary to suit conditions encountered in any particular

make of car; thus the arm 4 may project either forwardly or to the rear of the foot rest instead of laterally therefrom.

The rest is thus reciprocably supported by means of a plate 5 mounted on a guide frame 6 that is conveniently disposed below the floor, a compression spring 7 being interposed between such plate 5 and the rest so as to further relieve pedal 1 of any load 10 should this be found necessary. In addition to the reciprocal movement of the rest 3 thus provided for, such rest is rendered transversely movable on plate 5 by being connected therewith through the medium of pins 7 on one of the members in question that fit in slots 8 on the other. Such transverse movement, it will be observed, is limited by the connecting means in question so that the arm 4 is at no time disengaged 15 from pedal 1.

Mounted on foot board 2 adjacent the foot rest 3 is a tubular casing 10, of general cylindrical form, open on the side directed towards said rest, and in such casing is 20 housed a coil spring 11 in slightly compressed state, but preferably with the convolutions thereof somewhat spaced apart, as shown in Figs. 2 and 3. Projecting from the adjacent side of the rest is a pawl or 25 finger 12, the outer end of which is preferably slightly beveled, such finger being so located with reference to the casing 10 that upon slight lateral movement of the rest towards said casing, it may be caused to 30 enter between any two selected convolutions of the spring and will be there held, thus retaining the rest in corresponding vertical position. Obviously the foot pedal will be held in corresponding depressed position, 35 giving whatever speed may be desired by the operator under the particular road conditions encountered at the time. If it is desired to change the setting of the pedal, it is merely necessary for the operator by a 40 slight lateral shifting movement of his foot to disengage finger 12 from spring 11 and again engage same therewith at a different elevation. The spring will preferably be 45 stiff enough so that the operator may rest his foot on the pedal, when set in the fashion 50 just described, without effect on the latter, but by a suitable increase in pressure, such spring may be additionally compressed a slight amount in order to accelerate the 55 speed of the vehicle as in going up a slight incline or passing another vehicle.

In the modified construction illustrated in Figs. 4 and 5, the foot rest 15 is shown as lying directly over and engaging with the 60 accelerator pedal 1 and said rest, and instead of being directly reciprocable, is oscillatorily mounted on a horizontal pivot 16 through the medium of an arm 17. The pivotal connection is made sufficiently loose 65 (or a universal joint may be employed in

stead thereof) so that a slight oscillatory movement of the rest in a horizontal plane may also be obtained. A torsion spring 18, corresponding in function with spring 7 in the first described construction, normally 70 tends to raise the foot rest and relieve the pedal 1 of any load, but upon depressing said rest and then shifting the same in a horizontal plane, a finger or pawl 19 thereon may be engaged between any two selected convolutions of a spring 20 that is held in a housing 21 located adjacent said rest and identical in every way with the housing 10 except that it is curved to correspond with the curvi-linear movement of 80 the finger 19 due to the oscillatory character of the mounting of the rest.

Instead of employing a spring to form the ratchet wherewith finger or pawl 12, or 85 19 as the case may be, is adapted to engage, I may employ an ordinary saw tooth ratchet 25, as shown in Fig. 6, the mounting of the foot rest 26 here illustrated being substantially the same as that just described in connection with the forms illustrated in Figs. 90 4 and 5. Said rest is provided as before with a pawl 27 that upon lateral shifting of the rest may be engaged with any selected tooth on the ratchet. It is not possible, however, with this construction to vary 95 the vertical position of the rest without disengaging such finger. Moreover, the use of a coil spring, when mounted as shown in Figs. 1, 2 and 3, for example, has the further advantage of permitting the nice adjustment of any selected point at which it 100 may be desired to set the device for normal operation, by simply rotating such spring about its axis. Thus, where a speed limit is imposed by municipal ordinance or otherwise, the spring may be rotated to present a convolution at exactly the right height for giving such speed when the pawl or finger 105 12 is engaged therewith; and this adjustment can be quickly and easily changed 110 when a change in carburetor adjustment or other conditions make it necessary.

Other modes of applying the principle of my invention may be employed instead of the one explained, change being made as regards the mechanism herein disclosed, provided the means stated by any of the following claims or the equivalent of such stated means be employed.

I therefore particularly point out and 120 distinctly claim as my invention:

1. In a control device of the character described, the combination of a movable foot-rest, and independently operable means adapted positively to retain said foot-rest 125 against movement in either direction from a selected position, said foot-rest being normally movable without any interference from said means.

2. In a control device of the character 130

- described, the combination of a movable foot-rest and means adapted to retain said foot-rest in selected position, said means including an independently operable element 5 carried by said foot-rest and an element adapted to be engaged by said first-named element, and one of said elements having limited movement in the direction of movement of said foot-rest.
- 10 3. In a control device of the character described, the combination of a movable foot-rest and means adapted to retain said foot-rest in selected position, said means including an independently operable element 15 carried by said foot-rest and an element adapted to be engaged by said first-named element, and one of said elements being resiliently maintained in normal position but having limited movement from such position 20 in the direction of movement of said foot-rest.
4. In a control device of the character described, the combination of a movable foot-rest and means adapted to retain said foot-rest in selected position, said means including an independently operable element carried by said foot-rest and an element adapted to be engaged by said first-named element, and one of said elements being adjustable 30 in the direction of movement of said foot-rest.
5. In a control device of the character described, the combination of a movable foot-rest and means adapted to retain said foot-rest in selected position, said means including an independently operable element carried by said foot-rest and an element adapted to be engaged by said first-named element, and one of said elements being adjustable 35 in the direction of movement of said foot-rest and in addition having limited movement in the same direction from such adjusted position.
6. In a control device of the character described, the combination of a movable foot-rest and means adapted to retain said foot-rest in selected position, said means including an independently operable element carried by said foot-rest and a series of elements 45 adapted to be selectively engaged by said first-named element and to have limited movement in the direction of movement of said foot-rest.
7. In a control device of the character described, the combination of a movable foot-rest and means adapted to retain said foot-rest in selected position, said means including an independently operable element carried by said foot-rest, and a coil spring 55 disposed to have its convolutions selectively engaged by said element.
8. In a control device of the character described, the combination of a movable foot-rest and means adapted to retain said foot-rest in selected position, said means including an independently operable element carried by said foot-rest, and a coil spring 60 disposed to have its convolutions selectively engaged by said element.
- cluding an independently operable element carried by said foot-rest, and a coil spring disposed to have its convolutions selectively engaged by said element and said spring being rotatable about its axis to adjust the 70 normal position of said convolution as presented for engagement by said element.
9. In a control device of the character described, the combination of a movable foot-rest, and independently operable means 75 adapted to retain said foot-rest in selected position, said foot-rest being normally movable without any interference from said means and the latter including a resilient member whereby limited movement is permitted said foot-rest.
10. In a control device of the character described, the combination of a foot-rest comprising two independently movable elements, one of said elements being adapted to engage an accelerator pedal or the like in order to depress the same as desired, and a member adapted to be engaged by the other element of said foot-rest and thereby retain the latter in selected position, said member having a limited movement in the direction of movement of the first-named element of said foot-rest.
11. In a control device of the character described, the combination of a foot-rest 85 comprising two independently movable elements, one of said elements being adapted to engage an accelerator pedal or the like in order to depress the same as desired, and a resilient member adapted to be engaged by 90 the other element of said foot-rest and thereby retain the latter in selected position.
12. In a control device of the character described, the combination of a foot-rest supported so as to be both vertically and transversely adjustable, said foot-rest being adapted to engage an accelerator pedal or the like in order to depress the same as desired, and means adapted to be engaged by 105 said foot-rest upon transverse movement thereof and to retain same in selected vertical position.
13. In a control device of the character described, the combination of a foot-rest supported so as to be both vertically and transversely adjustable, said foot-rest being adapted to engage an accelerator pedal or the like in order to depress the same as desired, and resilient means adapted to be engaged by 110 said foot-rest upon transverse movement thereof and to retain same in selected vertical position.
14. In a control device of the character described, the combination of a foot-rest supported so as to be both vertically and transversely adjustable, said foot-rest being adapted to engage an accelerator pedal or the like in order to depress the same as desired, a coil spring located adjacent to said foot-rest, and a finger on the latter adapted 115
15. In a control device of the character described, the combination of a foot-rest supported so as to be both vertically and transversely adjustable, said foot-rest being adapted to engage an accelerator pedal or the like in order to depress the same as desired, a coil spring located adjacent to said foot-rest, and a finger on the latter adapted 120
16. In a control device of the character described, the combination of a foot-rest supported so as to be both vertically and transversely adjustable, said foot-rest being adapted to engage an accelerator pedal or the like in order to depress the same as desired, a coil spring located adjacent to said foot-rest, and a finger on the latter adapted 125
17. In a control device of the character described, the combination of a foot-rest supported so as to be both vertically and transversely adjustable, said foot-rest being adapted to engage an accelerator pedal or the like in order to depress the same as desired, a coil spring located adjacent to said foot-rest, and a finger on the latter adapted 130

upon transverse movement thereof to be engaged between selected convolutions of said spring.

15. In a control device of the character described, the combination of a vertically reciprocable slide, a foot-rest mounted thereon so as to be transversely shiftable, said foot-rest being adapted to engage an ac-

celerator pedal or the like in order to depress the same desired; a coil spring located 10 adjacent to said foot-rest, and a finger on the latter adapted upon transverse movement thereof to be engaged between selected convolutions of said spring.

Signed by me this 27th day of May, 1922.
GEORGE F. CASTLE.
